UNITED STATES PATENT OFFICE

2,524,667

THERMOSTATIC CONTROL

Wayne E. Jenkins and Theodore H. Thiele, Los Angeles, Calif., assignors, by mesne assignments, to Domestic Thermostat Company, a corporation of California

Application October 29, 1945, Serial No. 625,212

6 Claims. (Cl. 74—2)

1

The invention relates to thermostatically operated safety valves of the type disclosed in U. S. Patent No. 2,322,520, issued to Wayne E. Jenkins on June 22, 1943, and more particularly to the construction and mounting of the bi-metal thermostat element of such a unit.

An object of the invention is to provide a unit of the character described wherein the bimetal element is so constructed and mounted relative to its associated coating parts as to better withstand the physical stress, the heating and the flexing to which it is subjected, whereby the unit will be more positive and reliable in its operation, perform its required precision movement with greater dependability, and have a much longer useful life than structures heretofore available.

Another object of the invention is to provide a construction of the character above which lends itself to large scale mass production on a relatively simple and inexpensive basis in manufacture and assembly, and wherein the end item is so formed and assembled as to insure such a degree of uniformity of the items produced as to substantially eliminate the requirement for factory setting of individual devices to an acceptable standard of performance.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to the drawing:

Figure 1 is a view partly in side elevation and partly in cross-section showing a thermostatically operated apparatus regulated by an improved thermostatic control of our invention. Certain of the parts are broken away to shorten the view.

Figure 2 is a perspective view of one type of bi-metal latch.

Figure 3 is a fragmental sectional view of a modified form of mounting.

Figure 4 is a fragmental side elevational view of a further modified form of control element and mounting.

Figure 5 is a fragmental side elevational view of still another modification of the control element and mounting therefor.

Figure 6 is an end elevational view of the structure shown in Figure 5.

The bimetal thermostat control structure of

2

the present invention may be used in various types of control devices. The device here selected for purposes of illustrating and describing the present invention is of the general type and construction disclosed in the above mentioned U. S. Letters Patent No. 2,322,520 to which reference is made for a more complete showing and description of operating parts not specifically involved in the present invention. The device here shown is a pilot-operated safety valve positioned in the fuel line to the main burner of a heating appliance, such as a water heater, furnace, or the like, and which functions automatically to shut off the flow of fuel to the main burner should the pilot burner, used for igniting the main burner, be accidentally or otherwise extinguished. With reference to Figure 1 of the drawing, the device comprises a valve housing 7 provided with an inlet chamber 8, supplied with fuel from a supply pipe 9, and an outlet chamber 11, fitted with an outlet pipe 12 through which fuel may be supplied to a main burner, not shown. A port 13 in the valve housing 7 provides communication between the chambers 8 and 7 and may be opened or closed by a spring-pressed poppet valve 14 located in the chamber 8. A control rod 16, coaxially connected with the valve stem 17, is mounted for movement in a tube 18, connected into and projecting from a boss 19 formed on the side of the valve housing, the outer end of the rod terminating within a metallic capsule 21 which is carried by a collar 22 fixedly secured to the outer end of the tube 18. A bushing 23, concentric with the outer end of the control rod 16, is provided with a threaded stem 24 engaged in a complementary threaded recess formed in the collar 22. A strip 26 of bimetal, paralleling the control rod 16, is secured in one of several ways, which will be presently described, to the sleeve 23 and has a free end formed with a lip 27 inturned toward the axis of the control rod. A pilot burner is provided, by means of which ignition of the main burner may be accomplished, which comprises a length of tubing 28 having an end secured in the boss 19 and paralleling the tube 18 to terminate in a closed end under or adjacent to the capsule 21. Fuel is supplied to the pilot tube through a separate fuel inlet 29 and may be ignited at the ports 31 so that the resulting flame will heat the capsule 21 and the bimetal strip 26 therein. The strip 26 is arranged with its lamination possessing the greater coefficient of heat expansion on the outer or side thereof remote from the axis of the control rod so that heating will cause the strip to flex radially

inwardly toward the control rod. Thus, if the pilot flame is burning, the lip 27 of the strip will press against the side of the rod and when the reset button 32 is pulled outwardly, the valve 14 will open to permit fuel flow from the supply line 9 to the main burner and, since the control rod moves correspondingly, the lip 27 will snap over the end of the rod as shown in the drawing and will hold the valve 14 open thereafter. If, due to any reason, the pilot flame should become extinguished, the cooling bimetal strip will flex radially outwardly of the capsule and withdraw the lip 27 thus freeing the control rod and permitting the valve 14 to close under the pressure of its associated spring to effect shutting off of the flow of fuel to the main burner, which flow may not then be reinstated until the pilot burner is again ignited and the safety valve is latched in its open position.

We have successfully employed several different means for attachment of the fixed end of the bimetal strip to the structure of the guide sleeve 23, each of which is functionally identical in that the mounting in no way modifies the flexing action of the strip. In the type of sleeve structure shown in Figure 1, we provide an integral collar 33 in which an annular groove 34 is formed. The bimetal strip associated with this type of mounting is shown in Figure 2 and comprises a pair of integral tabs 36, formed with and extending from the strip 26, which are shaped to circular form and are pressed into the groove 34, the latter being slightly deeper than the width of the tabs so that bordering metal of the groove may be peened over thereinto in effecting a secure lock for the tabs in the groove. In Figure 3, we have shown another method of accomplishing this result. In this case, the collar 37 is a separate piece and is provided with an axial counterbore 38 cooperative, with the extended sleeve 23, to form an annular recess, equivalent to the recess 34, for receiving the tabs 36. The sleeve 23 of course is a tight press fit in the bore of the collar 37 and an annular shoulder 39 formed on the sleeve overlies the counterbore 38 and secures the tabs 36 in the annular recess. It is necessary in this structure however to notch out the shoulder 39 in order to provide clearance for the strip 26 which axially traverses it. In Figure 4 we have illustrated another form of mounting comprising a keyhole-shaped or similarly figured recess 41 which may be end-milled into the side of the sleeve structure 42, which in this case may be a unitary piece, the end of the bimetal strip 26 being formed with a coextensive tab 43 complementary in shape with the recess 41 and fitting thereinto. Metal bordering the recess may be peened over the tab 43 so as to lock the latter securely in place. In Figures 5 and 6 we have shown still another modified form of mounting. In this case the unitary sleeve member 23 is provided, at a desired radial distance from the axis of the member, with a chordal slot 44 into which the end of the bimetal strip 26 may be sweated or otherwise securely anchored.

As one of the principal features of the present invention, it should be particularly noted that, in all of the anchoring structures shown in the drawing, the bimetal strip, as it extends through its nodal point, that is, the plane separating its inactive and actively flexible portions, is co-planar with the inactive and active portions in alignment in contrast to the bent type of strip shown in the above mentioned patent. Thus no structural alteration in the metal at the so-called

nodal point, equivalent to that in the bent types of bimetal strips, is present and full power and sensitiveness in the strip is preserved. It will be obvious therefore that, since the combined active and inactive portions of the strip are composed of a single piece of unaltered material, it is possible to turn out the bimetal strips in large quantities with the assurance that the operational characteristics of respective strips will be substantially identical, all other factors being equal. The time-saving value of such a result, in the inspection, calibration and adjustment that is eliminated, will be especially apparent to those who employ volume production in their plants, as will the ease of assembly provided by the various types of mountings.

We claim:

1. In a thermostatic control device, a movable control rod, a relatively fixed sleeve concentric with said control rod and provided with a concentric recess, a bimetal element disposed adjacent said control rod and having a portion thereof flexible under the application of heat thereto toward said control rod, said element having at one end thereof an offset portion movable during said flexure into engagement with and to hold said control rod against movement, and said element at the other end thereof having an integral circularly formed anchor portion entering and secured in the recess of said sleeve, and said anchor portion and said flexible portion being joined in a straight line through an intermediate point of flexure and with line substantially parallel to said rod.
2. In a thermostatic control device, a movable control rod, a relatively fixed sleeve concentric with said control rod and provided with a recess extending longitudinally of and radially entering a peripheral surface of said sleeve, a bimetal element disposed adjacent said control rod and having a portion thereof flexible under the application of heat thereto toward said control rod, said element having at one end thereof an offset portion movable during said flexure into engagement with and to hold said control rod against movement, and said element at the other end thereof having an integral anchor portion thereof complementary to, entering and secure in said recess, and said anchor portion being coextensive and lying in a common plane with said flexible portion of said element.
3. In a thermostatic control device, a movable control rod, a relatively fixed sleeve concentric with said control rod and provided with a recess extending chordally across said sleeve in radially offset relation to the axis thereof, a bimetal element disposed adjacent said control rod and having a portion thereof flexible under the application of heat thereto toward said control rod, said element having at one end thereof an offset portion movable during said flexure into engagement with and to hold said control rod against movement, and said element at the other end thereof having an integral anchor portion keyed in said recess, and said anchor portion being co-extensive and lying in a common plane with said flexible portion of said element.
4. In a thermostatic control device, a movable control rod, a relatively fixed sleeve concentric with said control rod, a collar secured on said sleeve having therein a counterbore cooperative with a portion of the sleeve to form a concentric recess about the control rod axis, a bimetal element disposed adjacent said control rod and having a portion thereof flexible under the applica-

tion of heat thereto toward said control rod, said element having at one end thereof an offset portion movable during said flexure into engagement with and to hold said control rod against movement, and said element at the other end thereof having an integral anchor portion complementary to and, entering and secured in said recess, and said anchor portion being joined to said flexible portion in a straight line through an intermediate point of flexure and substantially parallel to said rod.

5. In a thermostatic control device including a relatively fixed collar and a control rod mounted for reciprocation therein and having one end thereof projecting from an end face of said collar and being spring loaded for movement away from said collar face, said collar being formed with a recess opening to said face and having a depth dimension parallel to the axis of said rod, an elongated bimetal element having a relatively fixed end portion mounted and secured in said recess and a contiguous flexible portion extending from said end portion with a nodal point at said collar face, said flexible portion extending generally parallel to said axis in spaced relation to said rod and swinging to and from said rod from said nodal point in response to change in temperature, the opposite end of said element being bent at substantially right angles to the length thereof in the direction of said rod and having an offset dimension sufficient to latch over the outer end of said rod to hold it against outward movement under the influence of said spring loading upon appropriate heating of said element, said element being subjected in said latched position to longitudinal tensional strain and said flexible portion being joined to said first end portion in a substantially straight line passing through said nodal point.

6. In a thermostatic control device including a relatively fixed collar of annular form and a control rod mounted substantially axially there-

through for longitudinal reciprocation and having one end projecting from an annular end face of said collar, spring means normally urging said rod end outwardly from said collar face, said collar being formed with a substantially circular recess substantially concentric to said rod and opening to said face and having a depth-wise dimension substantially parallel to the axis of said rod, a bimetal element having a substantially annular base portion mounted and secured in said recess with an elongated flexible portion extending therefrom in substantially parallel relation to said axis and joined to said base portion in a nodal point for relative flexure of said elongated portion, said elongated portion constructed to swing from said nodal point to and from said rod in response to change in temperature, the opposite free end of said element being bent at substantially right angles to the length thereof in the direction of said rod to latch over said outer rod end for holding said rod against outward movement under the influence of said spring means, said element being subjected in latched position to longitudinal tensional strain and said elongated flexible portion being joined to said annular base portion in a substantially straight line passing through said nodal point.
